UNITED STATES PATENT OFFICE.

JAMES W. BERRY, OF IOWA CITY, IOWA.

FENCING.

SPECIFICATION forming part of Letters Patent No. 741,216, dated October 13, 1903.

Application filed August 22, 1902. Serial No. 120,663. (No model.)

To all whom it may concern:

Be it known that I, JAMES W. BERRY, a citizen of the United States, residing at Iowa City, in the county of Johnson and State of Iowa, have invented a new and useful Fencing, of which the following is a specification.

This invention relates to fencing, more particularly to the class known as "woven-wire" fencing, and has for its object the production of a fencing which may be cheaply constructed and be of ample strength and yieldable, so that it will adapt itself preferably to irregularities of the ground without "buckling" or showing wave-lines; and the invention consists in a fencing formed of spaced strand-wires connected by mesh-wires reversely looped to the strand-wires and movable longitudinally thereon, whereby the fencing is rendered flexible, so that it will adapt itself to the irregularities of the ground.

Other novel features of the invention will appear in the following description and be specified in the claim.

In the drawings illustrative of the invention, Figure 1 is a side elevation of a section of the improved fencing. Fig. 2 is an enlarged detail illustrating a modification in the construction of the yieldable joint between the strand-wires and loops or mesh-wires. Fig. 3 represents a side elevation of an enlarged detail showing the upper mesh-wire and the line-wire in full lines and the lower mesh-wire in dotted lines, the crimp being clearly shown. Fig. 4 represents an enlarged detail view of the form shown in Fig. 2, the line-wire being shown in section and one mesh-wire only being shown.

In this fencing is comprised a plurality of spaced strand-wires 10, preferably horizontal or disposed substantially parallel to the ground, and reversely-disposed mesh-wires 11, the latter looped at intervals loosely about the strand-wires from opposite sides, as shown, so that when arranged in series the mesh-wires form diagonal strands with relation to the horizontal strand-wires, and are yieldably coupled to the strand-wire and movable longitudinally thereon, so that the panels of fencing when connected to the posts will readily conform to the ground (indicated at 13) no matter how irregular the latter may be.

For the purpose of illustration the ground is shown irregular in outline to illustrate the adaptability of the fence to the varied surfaces of the ground over which it will be placed.

Each section of the mesh-wire 11 is looped alternately back and forth between adjacent pairs of the strand-wires, as shown, and the sections are reversely looped about each other and the intermediate strand-wire at their meeting points at 14, as shown.

In constructing the fence the mesh-wires will be in reversely diagonally disposed bends and looped from opposite sides around the strand-wires, thus forming a very strong complete fence which will yield vertically, as above noted, to cause it to conform to the irregularities of the ground over which it is erected, as the loops between the strand-wires and mesh-wires permit the mesh-wires to move upon the strand-wires, as will be understood.

At suitable intervals the strand-wires may be reinforced by the insertion of one or more cable-wires 17, the cable-wires replacing an equal number of the ordinary strand-wires, the cable-wires being formed by twisting two or more of the strand-wires together, as shown. The upper strand-wire 10 may likewise be replaced by one of the cable-wires, or an additional strand-wire may be employed at this point, as shown in Fig. 1, to strengthen the upper edge of the fence. These modifications, however, will not be a departure from the principle of the invention, as the results produced are not modified by their presence.

The diagonal mesh-wires will be looped around the cable-wires in the same manner as around the ordinary strand-wires, as shown, and the yieldableness of the fence is not affected by their presence. These extra cable-strands may be added at as frequent points as required, but for the purpose of illustration they are shown inserted at every fourth strand-wire; but I do not wish to be limited in any manner to the number employed, as they may be inserted as often as required or left out altogether, as they are not required in some forms of fencing.

In Fig. 2 a slight modification in the construction is shown, consisting in "crimping" the mesh-wires 11 together, as at 18, in close

proximity to the strand-wires 10, which while not interfering in any manner with the flexibility of the fence or with its ability to readily yield to the inequalities of the ground will, 5 nevertheless, materially strengthen and stiffen it. In this form the loops do not pass through each other, as in Fig. 1, but are crimped, as at 18, the end of one loop engaging the crimp of the adjacent loop, the strand-wire passing 10 through said loops.

When the fencing is detached from the posts, it may be readily rolled for convenience of transportation.

The gage of wire employed may be varied 15 to any desired extent, and the fence thus constructed of any required strength.

The strand-wires and the coacting mesh-wires may be spaced any desired distance to increase or decrease the area of the openings 20 between the meshes to adapt the fence to the different purposes for which this class of fence is usually employed.

When employed for an ordinary field-fence or pasture-fence, the meshes may be very 25 much larger than when employed for fencing poultry-yards and for similar purposes, and it will be readily understood that the improvement is readily adaptable to all of these

various purposes and uses. By this arrangement of fencing the strand-wires may be 30 placed at irregular intervals, if required, without affecting the mesh-wires, which will readily adapt themselves to this modification. By this means the mesh may be woven finer near the lower part of the fence when employed to 35 guard inclosures containing smaller animals and fowls and is an important feature of the invention and adds materially to the usefulness and efficiency of the device.

Having thus described the invention, what 40 is claimed is—

A wire fencing consisting of spaced strand-wires having mesh-wires reversely looped thereon, with the loops crimped upon opposite sides of the strand-wires and movable thereon, the looped end of one mesh-wire engaging the crimp of the adjacent reversely-looped 45 mesh-wire.

In testimony that I claim the foregoing as my own I have hereto affixed my signature in 50 the presence of two witnesses.

JAMES W. BERRY.
